CLAIM

The ornamental design for the apple shaped dispenser, as shown and described.

DESCRIPTION

FIG. 1 is a perspective view for an apple shape thereof; FIG. 2 is a top plan view for an apple shape thereof; FIG. 3 is a front elevation view for an apple shape thereof; FIG. 4 is a rear elevation view for an apple shape thereof; FIG. 5 is a left side elevation view for an apple shape thereof;

FIG. 6 is a right side elevation view for an apple shape thereof; and,

FIG. 7 is a bottom plan view for an apple shape thereof. The dashed line showing in FIG. 7 showing the design as a dental floss dispenser is for illustrative purposes only, and forms no part of the claimed design.
